UNITED STATES PATENT OFFICE.

JOHN H. WHEELOCK AND GEORGE M. WRIGHT, OF WORCESTER,
MASSACHUSETTS.

ANCHORAGE FOR WIRE FENCING.

No. 805,764.

Specification of Letters Patent.

Patented Nov. 28, 1905.

Application filed January 19, 1905. Serial No. 241,738.

To all whom it may concern:

Be it known that we, JOHN H. WHEELOCK and GEORGE M. WRIGHT, citizens of the United States, residing at Worcester, in the county 5 of Worcester and State of Massachusetts, have invented a new and useful Anchorage for Wire Fencing, of which the following is a specification.

This invention relates to that class of wire 10 fencing which consists of vertical wires and cross-wires connected together by sheet-metal joint-clips.

The especial object of this invention is to provide a strong, simple, and adjustable means 15 for fastening wire fencing to posts or other supports.

To these ends this invention consists of the anchorages for wire fencing and of the combinations of parts therewith, as hereinafter 20 described, and more particularly pointed out in the claims at the end of this specification.

In the accompanying drawings, Figure 1 is a side view of a fence-post and of sufficient 25 part of a wire fence to illustrate the application of this invention thereto. Fig. 2 is an enlarged view of one of the fastening-fixtures. Fig. 3 is a similar view showing the same applied to one of the sheet-metal joint-clips. Fig. 4 is a detail view of a joint, showing the 30 end of a horizontal wire bent back to form a hook; and Fig. 5 is a detail view showing the position of the ends of the fastening-fixture before the same are bent down.

In that class of wire fencing to which this 35 invention relates one of the best and most practical forms of construction is made by use of special sheet-metal joint-clips connecting vertical wires to cross-wires.

In the particular form of sheet-metal clip 40 illustrated the clip is provided with top and bottom ears having perforations which receive one of the vertical wires. The body portion of the clip has a groove receiving a horizontal wire. When this form of clip is fastened 45 in place by being more or less flattened or opened out, the two fence-wires will be more or less shaped to form interlocking bends. In the special construction which we have devised for fastening a wire fence of this character to 50 one of its posts or supports we make use of a special hook-piece, which receives one of the sheet-metal joint-clips.

Referring to the drawings and in detail, the

wire fence herein illustrated comprises the vertical fence-wires 10 and the horizontal 55 cross-wires 11. The vertical wires are preferably connected at their upper ends by loops, so that two of the vertical wires form a wicket. Fastening the vertical and cross wires together are the sheet-metal clips 12. Each of 60 these clips, as shown in Fig. 4, is provided with perforations 13, through which one of the vertical wires is threaded, while the body portion of the clip is grooved to receive one of the horizontal wires 11, and at each end clip 65 of a section of fencing the horizontal wire 11 is bent or turned back upon itself to form a hook or turned-over end 15.

The anchorages for fastening the end clips to a fence-post P each consists of a malleable 70 casting 16, having ears 17 and a barrel or hub 18. Fitting loosely to the barrel or hub 18 is a screw 19, which is held in place by a head 20. The end of the screw extends through the post, as shown, and is drawn back through 75 the post by means of a nut 21.

By making the body portion of the hook 16 of malleable iron the hooked fingers 17 may be cast in the form shown in Fig. 5, and after the sheet-metal clip is fitted into place 80 by turning over the fingers 17 the clips may be more or less firmly locked or fastened in place and the body portion 16 will inclose the bent-back end 15 of a cross-wire, so that it will not only protect the loose end of the wire, 85 but will also prevent the hook 15 of the wire from straightening out under the heavy tension required for stretching the fence as desired.

We are aware that changes may be made in 90 applying our construction to wire fencing. We do not wish, therefore, to be limited to the particular form we have herein shown and described; but—

What we do claim, and desire to secure by 95 Letters Patent of the United States, is—

1. In a wire fence, the combination of a vertical wire, a cross-wire, a sheet-metal joint-clip fastening said wires together, a hook-piece receiving the joint-clip, and means for 100 connecting the hook-piece to a post or other support.

2. In a wire fence, the combination of a vertical wire, a cross-wire, a sheet-metal joint-clip connecting the vertical wire and cross-wire while the end of the cross-wire is turned 105

back to form a hook, a hook-piece receiving the joint-clip, and means for connecting the hook-piece to a post or other support.

3. In a wire fence, the combination of a vertical wire, a cross-wire, a sheet-metal joint-clip having two perforations through which the vertical wire is threaded, while the cross-wire is bent back or hooked at its ends, a hook-piece receiving the joint-clip and having hooked ends engaging the joint-clip at opposite sides of the cross-wire, a screw extending from the hook-piece, and a nut for tightening the hook-piece in place with reference to a post or support.

15 4. In a wire fence, the combination of a vertical wire, a cross-wire, a sheet-metal joint-clip having two perforations through which the vertical wire is threaded, while the cross-

wire is hooked or bent back at its ends, a hook-piece receiving the sheet-metal clip and having malleable or flexible fingers which are bent and engage the joint-clip at opposite sides of the cross-wire, a screw having a head holding the same in place in the hub of the hook-piece, and a nut threaded onto the screw 25 for tightening the hook-piece into place with respect to a post or support.

In testimony whereof we have hereunto set our hands in the presence of two subscribing witnesses.

J. H. WHEELOCK.
GEORGE M. WRIGHT.
